ALARM CLOCK

Albert B. Reichenbach, Waterbury, Conn., assignor to The Waterbury Clock Company, Waterbury, Conn., a corporation of Connecticut

Application November 21, 1936, Serial No. 112,091

13 Claims. (Cl. 58—16)

This invention relates to an improvement in clocks, and particularly to that class of audible-signal clocks commonly referred to as "alarm" clocks.

5 One of the objects of the present invention is to provide a superior alarm clock in which the beat-frequency of the alarm-mechanism is sufficiently slow as not to occasion undue shock to a sleeper.

10 A further object is to provide a superior alarm clock in which the beat-frequency of the alarm-sounding means is determined by the time-train.

Another object of the present invention is to provide a superior spring-driven alarm clock embodying both a spring-driven time-train and a spring-driven alarm-train and in which the beat-frequency of the alarm-sounding means is modulated without recourse to complex governing means.

20 Still another object of the present invention is to provide an alarm clock having superior means for providing a multiple-phase alarm-cycle, during one phase of which the alarm is moderate and during the subsequent phase of which the alarm is more violent.

25 A still further object is to provide a superior alarm clock in which the alarm-train, instead of being a burden upon the operation of the time-train, will exert an effort to assist the said time-train when the alarm-train is released.

With the above and other objects in view, as will appear to those skilled in the art from the present disclosure, this invention includes all features in the said disclosure which are novel over the prior art and which are not claimed by me in a separate application.

In the accompanying drawings:

Fig. 1 is a view in rear elevation of an alarm clock embodying the present invention with portions of the rear movement-plate broken away;

40 Fig. 2 is an edge view thereof;

Fig. 3 is a view in rear elevation of the alarm-train detached, together with a portion of the time-train, the parts being shown in the positions 45 which they assume when the alarm-governing pawl overrides the alarm-governing wheel;

Fig. 4 is a similar view but showing the frequency-changing member acting to retire the frequency-governing pawl, to thus leave the alarm-train free of outside restraint;

Fig. 5 is a detail sectional view taken on the line 5—5 of Fig. 4 and also showing the front and rear movement-plates;

55 Fig. 6 is a perspective view of the frequency-changing member;

Fig. 7 is a perspective view of the unit comprising the verge-arbor, verge and alarm-stop arm;

Fig. 8 is a perspective view of the hammer or striker; and

Fig. 9 is a similar view of the frequency-governing pawl.

The particular alarm clock herein chosen for the illustration of the present invention includes a front movement-plate 20 and a rear movement-plate 21 held in rigid spaced relationship by interconnecting pillars 22. The movement-plates just referred to mount (mostly in the space between them) both a time-train and an alarm-train having characteristics which will be more fully 15 hereinafter described.

The time-train includes a main- or winding-arbor 23 journaled in the movement-plates 20 and 21 and which, in the usual manner of the art, mounts a mainspring 24, the driving-urge of 20 which latter is transmitted to a main-wheel 25 through the intermediary of a ratchet-wheel 26 and a pawl 27. The main-wheel 25 meshes into and drives a first-pinion 28 of the lantern type which is rigidly mounted upon and serves to drive 25 the center- or minute-arbor 29 of the time-train. The first-pinion 28 is rigidly attached to a second-wheel 30 which meshes into and drives a second-pinion 31 mounted upon an arbor 32 journaled in the movement-plates 20 and 21. The arbor 32 just referred to has rigidly attached to it 30 a third-wheel 33 which meshes into and drives a third-pinion 34 of the lantern type which, together with a fourth-wheel 35, is rigidly mounted upon an arbor 36 journaled at its respective 35 opposite ends in the movement-plates 20 and 21 respectively.

The fourth-wheel 35 of the time-train just referred to meshes into and drives a fourth-pinion 37 of the lantern type which is rigidly attached to an arbor 38 journaled in the movement-plates 20 and 21. The arbor 38, in the manner usual in time-trains, has rigidly secured to it an escape-wheel 39 which coacts with pallet-pins 40—40 in a pallet 41 mounted upon an arbor 42 intermediate the ends thereof. The arbor 42 just referred to has rigidly secured to it an impulse-arm 43 cooperating with an impulse-pin 44 carried by a balance-wheel 45, which latter is mounted upon a usual balance-staff 46. The balance-staff 46 carries a usual hair-spring 47 having its inner end attached thereto and its opposite end fastened to a bracket 48 forwardly projecting from the rear movement-plate 21.

The projecting forward end of the center- or 55

minute-arbor 29 carries a minute-hand 49 and has loosely journaled upon it an hour-sleeve 50 carrying an hour-hand 51, as shown in Fig. 2. The hour-sleeve 50 is formed as a unit with an hour-wheel 52 turning freely on the center-arbor 29 and which is driven by a dial-pinion 53 rotating upon a stud 54 forwardly offsetting from the front movement-plate 20. The dial-pinion 53 carries a dial-wheel 55 which meshes into and is driven by a minute-pinion 56 rigidly attached to the center- or minute-arbor 29 immediately in front of the front movement-plate 20.

Meshing into and driven by the dial-pinion 53 before described is an alarm-control wheel 57 rigidly carrying a sleeve-like alarm-control cam 58 and journaled upon the projecting forward end of an alarm-set staff 59 which latter is in turn journaled in both of the movement-plates 20 and 21. In the usual manner of alarm clocks, the sleeve-like alarm-control cam 58 is provided in its forward edge with a notch 60 which is adapted to receive an alarm-control finger 61 rigidly attached to and radially offsetting from the extreme forward portion of the alarm-set staff 59. Also in the usual manner of alarm clocks, the alarm-control wheel 57, together with the cam 58, is urged forwardly by a sheet-metal alarm-control spring 62 which is secured at its outer end to the forward face of the front movement-plate 20 by means of a stud 63. At its inner or free end the alarm-control spring 62 is bent to form an alarm-control finger 64 which, under the control of the cam 58 and the alarm-control finger 61, moves into and out of the path of oscillation of an alarm-stop arm 65.

The alarm-stop arm 65 just above referred to forms a feature of the alarm mechanism and is rigidly attached at one end to a verge-arbor 66 journaled in the front and rear movement-plates 20 and 21. The said verge-arbor 66 has rigidly attached to it a verge 67 which is vibrated in a manner usual in alarm mechanisms, by a toothed verge-wheel 68 which is staked upon an arbor 69 journaled in the front and rear movement-plates 20 and 21. In addition to the verge-wheel 68, the arbor 69 has staked to it a lantern-pinion 70 which meshes into and is driven by an alarm main-wheel 71 mounted upon the main-arbor 72 of the alarm-train. The said arbor 72 is driven by a spiral alarm-mainspring 73 through the usual intermediary of a ratchet-wheel 74 and a pawl 75.

The verge 67 is provided with an offsetting hammer-actuating arm 76 to the lower end of which is pivoted the adjacent end of a link 77 having its opposite end pivotally connected to a hammer or striker 78. The said hammer is rigidly mounted intermediate the movement-plates 20 and 21 upon a hammer-staff 79 which is journaled in the said movement-plates. The hammer 78 is preferably formed of sheet-metal and is provided with an enlarged terminal constituting a hammer-head 80 which is adapted to strike a bell or other sounder 81 indicated by broken lines in Fig. 1.

Pivotedly mounted upon the link 77 by means of a stud 82 is a frequency-governing pawl 83, preferably formed of sheet-metal and having a nose 84 which is adapted to engage the ratchet-like teeth of a frequency-governing wheel 85 staked upon the arbor 36 which carries the fourth-wheel 35 of the time-train. The pawl 83 is provided adjacent the respective opposite side-edges of the link 77 with two forwardly-projecting fingers 86 and 87, the former of which is

adapted to limit the upward swinging movement of the pawl, and the latter of which is designed to be engaged by a member which will prevent the nose 84 of the said pawl from engaging with the wheel 85 in a manner as will hereinafter appear. The pawl 83 also has a perforated finger 88 bent rearwardly from it, through which extends the free end of a wire-like spring 89 swaged into the slotted rear end of the stud 82 upon which the said pawl 83 swings.

For the purpose, on occasion, of preventing the nose 84 of the pawl 83 from engaging with the frequency-governing wheel 85 so as to permit the hammer or striker 78 to vibrate freely in a manner as will hereinafter appear, an L-shaped frequency-changing member, generally designated by the numeral 90, is employed. The said frequency-changing member 90 includes a cam-like nose 91 offsetting from the outer end of a radial arm 92 which is mounted for swinging movement upon a collet 93 rigidly fastened upon the main-arbor 72 of the alarm-train. The said member 90 is frictionally coupled to the collet 93 by being urged against the flange-terminal thereof by a helical spring 94 encircling the said collet. The degree of friction between the member 90 and the collet 93 is sufficient to cause the nose 91 of the said member to swing in a clockwise direction, as viewed in Figs. 1, 3 and 4, and suspend the action of the pawl 83 without, however, preventing the turning of the main-arbor 72.

To limit the clockwise turning movement of the frequency-changing member 90, the said member is bent up to provide a rearwardly-projecting stop-finger 95 which engages on occasion with a stop-finger 96 forwardly projecting from the rear movement-plate 21. The counterclockwise turning movement of the frequency-changing member 90, which occurs during the winding of the alarm-spring 73, is limited by the engagement of the said member with the arbor 69 of the verge-wheel 68.

The parts 83, 85 and 90, or their equivalents, may be viewed jointly as constituting beat-frequency-governing means, since the said parts in effect cause on one hand the retardation of the vibrations of the striker 78 under the driving urge of the verge-wheel 68, and then release the said striker for free vibration by the said verge-wheel, all in the manner as will hereinafter appear.

For the purpose of describing the operation of the alarm-clock movement herein illustrated, let it be presumed that the mainspring 24 of the time-train is wound and that the said train is running, and further that the mainspring 73 of the alarm-train has been wound by turning the main-arbor 72 in a counterclockwise direction, as viewed in Figs. 1, 3 and 4, to thus bring the frequency-changing member 90 into a retired position, as shown in Figs. 1 and 3. In this connection, it is to be explained that the turning of the main-arbor 72 in a counterclockwise direction to wind the alarm-mainspring 73, as described, is permitted by reason of the fact that the frequency-changing member 90 is frictionally attached to the said arbor, and when in a winding operation it strikes the verge-wheel arbor 69, the said main-arbor may be further rotated to complete the winding of the said spring 73.

When in the usual course of the operation of the clock, the notch 60 in the alarm-control cam 58 comes into registration with the alarm-control finger 61 on the alarm-set staff 59, the sheet-metal spring 62 will flex forwardly and axially slide the said cam, together with the wheel 57, in

the same direction. The forward flexing of the spring 62 will effect the retirement of its alarm-control finger 64 out of the path of the alarm-stop arm 65, whereupon the alarm-mainspring 73, acting through the verge-wheel 68 and verge 67, will be free to urge the link 71 and hence the pawl 83 and hammer or striker 78 to the left from the positions in which they are shown in Fig. 1. This advance from right to left will, however, be

retarded by the engagement of the nose 84 of the said pawl with the frequency-governing wheel 85 which is being turned but relatively slowly by the time-train, in the direction indicated. Thus, the urge of the alarm-mainspring to vibrate the hammer or striker 78 will be retarded and the energy of the said spring will be applied in assisting in the turning of the said wheel 85, and hence assisting the mainspring to operate the entire time-train.

As the particular tooth of the wheel 85 with which the pawl-nose 84 is engaged reaches substantially its topmost position, the said pawl-nose will be forced out of engagement with the said tooth by the next-succeeding tooth and will slide over the periphery of the said wheel to the limit of its movement to the left, thus permitting its associated parts to assume the positions shown in Fig. 3. The verge 67 will now immediately move the parts back to substantially the positions in which they are shown in Fig. 1 and thus cause the hammer-head 80 to strike the bell or sounder 81.

The cycle above described will now be repeated at relatively-long intervals (five seconds, for instance), depending upon the peripheral speed of the frequency-governing wheel 85. After a predetermined number of cycles, as described, the alarm-mainspring 73, in its unwinding, will turn the main-arbor 72 and the frequency-changing member 90 in a clockwise direction until the cam-like nose 91 of the said member rides under the finger 87 of the pawl 83 to a degree sufficient to prevent the nose 84 of the same from engaging with the teeth of the wheel 85. As soon as the pawl 83 is in effect rendered inoperative by the member 90, as described, the verge 67 and verge-wheel 68 will cause the rapid vibration of the hammer or striker 78, which under the conditions just described is free of any restraint by the time-train and may, therefore, vibrate at five beats per second, for instance.

When the finger 95 of the frequency-changing member 90 engages with the stop-finger 96 of the movement-plate 21, the clockwise turning movement of the said member will be checked, but the main-arbor 72 will continue to turn to actuate the hammer or striker 78, owing to the relatively-slight frictional coupling of the member 90 with the said arbor 72.

From the foregoing, it will be seen that the movement of the hammer or striker 78 or its equivalent may be so governed and reduced in frequency by the time-train acting through the wheel 85 as to produce a beat-frequency which will not unduly shock even the lightest of sleepers.

In the event that a sleeper is not sufficiently aroused by the relatively-slow beat-frequency of the alarm when the same is under the control of the pawl 83 and the wheel 85, the frequency-changing member 90 or its equivalent may be employed to free the alarm-mechanism of restraint by the time-train and thus permit the same to accelerate its beat-frequency.

The invention may be carried out in other

specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An alarm clock including in combination: a power-driven time-train; a power-driven alarm-train; a vibrating striker operatively connected to the said alarm-train for being vibrated thereby; and beat-frequency diminishing-means for forcibly diminishing the natural unrestrained beat-frequency of the said striker to a beat-frequency materially slower than the natural unrestrained beat-frequency thereof, and including two coacting members, one of which is operatively connected to the said alarm-train for being vibrated thereby concurrently with the said striker, and the other of which members is operatively connected to the said time-train by which it is driven, the two said coacting members being so constructed and arranged that the said vibrating member driven by the alarm-train assists in propelling the other of said coacting members.

2. An alarm clock including in combination: a power-driven time-train; a power-driven alarm-train; a vibrating striker operatively connected to the said alarm-train for being vibrated thereby; beat-frequency diminishing means for forcibly diminishing the natural unrestrained beat-frequency of the said striker to a beat-frequency materially slower than the natural unrestrained beat-frequency thereof, and including two coacting members, one of which is operatively connected to the said alarm-train for being vibrated thereby concurrently with the said striker, and the other of which members is operatively connected to the said time-train by which it is driven, the two said coacting members being so constructed and arranged that the said vibrating member driven by the alarm-train assists in propelling the other of said coacting members; and automatic means operatively-controlled by one of the said trains and being operable thereby during the driving-operation of the alarm-train at a predetermined time in the said driving-operation to automatically shift one of the two said coacting members of the beat-frequency diminishing-means out of coacting relationship with the other of said members to render the said means inoperative and permit the unrestrained continuous vibration of the said striker by the said alarm-train.

3. An alarm clock including in combination: a power-driven time-train; a power-driven alarm-train; a vibrating striker operatively connected to the said alarm-train for being vibrated thereby; beat-frequency diminishing means for forcibly diminishing the natural unrestrained beat-frequency of the said striker to a beat-frequency materially slower than the natural unrestrained beat-frequency thereof, and including two coacting members, one of which is operatively connected to the said alarm-train for being vibrated thereby concurrently with the said striker, and the other of which members is operatively connected to the said time-train by which it is driven, the two said coacting members being so constructed and arranged that the said vibrating member driven by the alarm-train assists in propelling the other of said coacting members; and a releasing member frictionally coupled to and

frictionally driven by the said alarm-train and engageable with the said vibrating member of the said beat-frequency diminishing-means to move the same out of coacting relationship with the other of said members to render the said means inoperative and permit the unrestrained continuous vibration of the said striker by the said alarm-train.

4. An alarm clock including in combination: a power-driven time-train; a power-driven alarm-train; a vibrating striker operatively connected to the said alarm-train for being vibrated thereby; and beat-frequency diminishing-means for forcibly diminishing the natural unrestrained beat-frequency of the said striker to a beat-frequency materially slower than the natural unrestrained beat-frequency thereof, and including a vibratable pawl operatively connected to the said alarm-train for being vibrated thereby concurrently with the said striker, and a toothed wheel coacting with the said pawl and operatively connected to the said time-train by which it is driven, the said vibratable pawl and the said toothed wheel being constructed and arranged so that the said pawl automatically slides off the said toothed wheel as the latter is turned by the time-train to permit the said striker to move for sounding a single-beat alarm.

5. An alarm clock including in combination: a power-driven time-train; a power-driven alarm-train; a vibrating striker operatively connected to the said alarm train for being vibrated thereby; beat-frequency diminishing-means for forcibly diminishing the natural unrestrained beat-frequency of the said striker to a beat-frequency materially slower than the natural unrestrained beat-frequency thereof, and including a vibratable pawl operatively connected to the said alarm-train for being vibrated thereby concurrently with the said striker, and a toothed wheel coacting with the said pawl and operatively connected to the said time-train by which it is driven, the said vibratable pawl and the said toothed wheel being constructed and arranged so that the said pawl automatically slides off the said toothed wheel as the latter is turned by the time-train to permit the said striker to move for sounding a single-beat alarm; and automatic means operatively-controlled by the said alarm-train and being operable thereby during the driving-operation of the alarm-train at a predetermined time in the said driving-operation to automatically shift the said vibratable pawl out of coacting relationship with the said toothed wheel to render the said beat-frequency diminishing-means inoperative and permit the unrestrained continuous vibration of the said striker by the said alarm-train.

6. An alarm clock including in combination: a power-driven time-train; a power-driven alarm-train; a vibrating striker operatively connected to the said alarm-train for being vibrated thereby; beat-frequency diminishing-means for forcibly diminishing the natural unrestrained beat-frequency of the said striker to a beat-frequency materially slower than the natural unrestrained beat-frequency thereof, and including a vibratable pawl operatively connected to the said alarm-train for being vibrated thereby concurrently with the said striker, and a toothed wheel coacting with the said pawl and operatively connected to the said time-train by which it is driven, the said vibratable pawl and the said toothed wheel being constructed and arranged so that the said pawl automatically slides off the said toothed wheel as the latter turns to permit the

said striker to move for sounding a single-beat alarm; and a pawl-releasing member driven by and frictionally coupled to the said alarm-train and engaging with the said vibrating pawl to retire the same out of coacting relationship with the said toothed wheel to permit the unrestrained continuous vibration of the said striker by the said alarm-train.

7. An alarm clock including in combination: a power-driven time-train; a power-driven alarm-train; a vibrating striker; a vibrating link operatively connecting the said striker to the said alarm-train for being vibrated thereby; a vibrating pawl pivotally carried by the said link; and a toothed wheel coacting with the said vibrating pawl and driven by the said time-train, the said vibrating pawl and the said toothed wheel being constructed and arranged so that said pawl automatically slides off the said toothed wheel as the latter turns to permit the said striker to move for sounding a brief alarm.

8. An alarm clock including in combination: a power-driven time-train; a power-driven alarm-train; a vibrating striker; a vibrating link operatively connecting the said striker to the said alarm-train for being vibrated thereby; a vibrating pawl pivotally carried by the said link; a toothed wheel coacting with the said vibrating pawl and driven by the said time-train, the said vibrating pawl and the said toothed wheel being constructed and arranged so that said pawl automatically slides off the said toothed wheel as the latter turns to permit the said striker to move for sounding a brief alarm; and a pawl-releasing member driven by and frictionally coupled to the said alarm-train and engaging with the said vibrating pawl to retire the same out of coacting relationship with the said toothed wheel to permit the unrestrained continuous vibration of the said striker by the said alarm-train.

9. An alarm clock including in combination: a power-driven time-train; a power-driven alarm-train; a vibrating striker operatively connected to the said alarm-train for being vibrated thereby; beat-frequency diminishing-means for forcibly diminishing the natural unrestrained beat-frequency of the said striker to a beat-frequency materially slower than the natural unrestrained beat-frequency thereof, and including two coacting members, one of which is operatively connected to the said alarm-train for being vibrated thereby concurrently with the said striker, and the other of which members is operatively connected to the said time-train by which it is driven, the two said coacting members being arranged in normally disengaged relation; a first one of the said members being operable by one of the said trains during the driving-operation of the alarm-train and at a predetermined time in the said driving-operation to be shifted into coacting engaging relation to the other of the said members, whereby vibration of the striker is restrained; and automatic means operatively-controlled by said one of the trains and operable thereby at another and later predetermined time in the said driving-operation of the said alarm-train to automatically shift the said first one of the two said coacting members of the beat-frequency diminishing-means out of coacting relationship with the other of said members to render the said means inoperative and permit the unrestrained continuous vibration of the said striker by the said alarm-train.

10. An alarm clock including in combination: a power-driven time-train; a power-driven

alarm-train; a vibrating striker operatively connected to the said alarm-train for being vibrated thereby; beat-frequency diminishing-means for forcibly diminishing the natural unrestrained beat-frequency of the said striker to a beat-frequency materially slower than the natural unrestrained beat-frequency thereof, and including two coacting members, one of which is operatively connected to the said alarm-train for being vibrated thereby concurrently with the said striker, and the other of which members is operatively connected to the said time-train by which it is driven, the two said coacting members being arranged in normally disengaged relation; the vibration member connected to the alarm-train being operable thereby during the driving-operation of the alarm-train and at a predetermined time in the said driving-operation, to be shifted into coacting engaging relation to the other of the said members, whereby vibration of the striker is restrained; and automatic means operatively-controlled by the said alarm-train and operable thereby at another and later predetermined time in the said driving-operation of the said alarm-train to automatically shift the said vibrating member of the beat-frequency diminishing-means out of coacting relationship with the other of said members to render the said means inoperative and permit the unrestrained continuous vibration of the said striker by the said alarm-train.

11. An alarm clock including in combination: a power-driven time-train; a power-driven alarm-train; a vibrating striker; a vibrating link operatively connecting the said striker to the said alarm-train for being vibrated thereby, and coacting members including a vibrating pawl pivotally carried by the said link, and a toothed wheel coacting with the said vibrating pawl and driven by the said time-train; the said vibrating pawl and toothed wheel being arranged in normally disengaged relation, and one of the said coacting members being operable by its controlling train connected therewith during the driving-operation of the alarm-train and at a predetermined time in the said driving-operation, to be shifted into engagement with the other of the said coacting members and effect coacting relationship between the said vibrating pawl and toothed wheel and the said vibrating pawl and the said toothed wheel being constructed and arranged so that said pawl automatically slides off the said toothed wheel as the latter turns to permit the said striker to move for sounding a brief alarm.

12. An alarm clock including in combination: a power-driven time-train; a power-driven alarm-train; a vibrating striker; a vibrating link operatively connecting the said striker to the said

alarm-train for being vibrated thereby, coacting members including a vibrating pawl pivotally carried by the said link, and a toothed wheel coacting with the said vibrating pawl and driven by the said time-train; the said vibrating pawl and toothed wheel being arranged in normally disengaged relation, and one of the said coacting members being operable by its controlling train connected therewith during the driving-operation of the alarm-train and at a predetermined time in the said driving-operation, to be shifted into engagement with the other of the said coacting members and effect coacting relationship between the said vibrating pawl and toothed wheel and the said vibrating pawl and the said toothed wheel being constructed and arranged so that said pawl automatically slides off the said toothed wheel as the latter turns to permit the said striker to move for sounding a brief alarm; and automatic means operable by the said controlling train at another and later predetermined time in the said driving-operation of the said alarm-train to automatically shift the said one of the two coacting members out of coacting relationship with the other of the said members to permit unrestrained continuous vibration of the vibrating striker by the said alarm-train.

13. An alarm clock including in combination: a power-driven time-train; a power-driven alarm-train; a vibrating striker; a vibrating link operatively connecting the said striker to the said alarm-train for being vibrated thereby; a vibrating pawl pivotally carried by the said link; a toothed wheel coacting with the said vibrating pawl and driven by the said time-train; the said vibrating pawl and toothed wheel being arranged in normally disengaged relation, and the said vibrating pawl being operable by the alarm-train during the driving-operation of the alarm-train and at a predetermined time in the said driving-operation, to be shifted into coacting engaging relation to the said toothed wheel; the said vibrating pawl and the said toothed wheel being constructed and arranged so that said pawl automatically slides off the said toothed wheel as the latter turns to permit the said striker to move for sounding a brief alarm; and a pawl-releasing member driven by and frictionally coupled to the said alarm-train and engaging at another and later predetermined time in the said driving-operation of the said alarm-train with the said vibrating pawl to retire the same out of coacting relationship with the said toothed wheel to permit the unrestrained continuous vibration of the said striker by the said alarm-train.

ALBERT B. REICHENBACH.
